FASTENING TOGETHER SHEETS OF
EXPANDED METAL

Theodore S. Okonski, Wheeling, W. Va., assignor,
by mesne assignments, to Wheeling Steel Cor-
poration, Wheeling, W. Va., a corporation of
Delaware

Application March 7, 1944, Serial No. 525,450

6 Claims. (Cl. 189—36)

1

This invention relates to fastening together sheets of expanded metal and particularly fastening together sheets of expanded metal to prevent separation of the sheets by relative movement in the plane of the sheets.

While the invention is of broad application it is especially well adapted for use in the making of road expedients, landing mats and the like which require the assembly of sheets of expanded metal so that when they are laid on the ground they will remain in predetermined relationship. Provision is made for ready disassembly of the sheets when desired.

I provide means for fastening together sheets of expanded metal comprising stop means connected with one sheet of expanded metal adapted to abut a portion of another sheet of expanded metal when the sheets are disposed with edges overlapping. Preferably the stop means has an operative portion or portions of hook form and is disposed at a point removed from the edge of the sheet to which it is connected and adapted to engage an edge portion of another sheet. Preferably the operative portion or portions of the stop means is or are positioned at a bond or bonds of the sheet of expanded metal to which the stop means is connected; a bond being where two strands are joined together. I find it desirable to connect the stop means with one strand of the expanded metal at one or more bonds and to form the stop means so as to project from said bond or bonds generally in the plane of the sheet and with the end or ends of the operative portion or portions thereof turned so as to intersect the plane of the sheet and extend generally in the direction of the other strand at said bond or bonds so as to engage over a portion or portions of another sheet of expanded metal when the sheets are disposed in overlapping relation with corresponding parts interfitting to prevent separation of the sheets by relative movement in the plane of the sheets. I preferably weld a bar carrying a number of stop members to each sheet along a line parallel to but removed from one edge thereof.

I also provide a composite structure comprising two sheets of expanded metal disposed in overlapping relation and nested at their edges and means connected with one of the sheets and engaging the other when the sheets are in said position to prevent separation of the sheets by relative movement in the plane of the sheets.

Other details, objects and advantages of the invention will become apparent as the following

2

description of a present preferred embodiment thereof proceeds.

In the accompanying drawings I have shown a present preferred embodiment of the invention, in which

Figure 1 is a fragmentary inverted plan view of the overlapped edges of two sheets of expanded metal fastened together in accordance with my invention;

10 Figure 2 is an enlarged fragmentary similarly inverted plan view of a portion of the structure shown in Figure 1;

Figure 3 is a plan view to the same scale as Figure 2 of a portion of the structure shown in

15 Figure 1;

Figure 4 is a cross-sectional view taken on the line IV—IV of Figure 3, but to enlarged scale;

20 Figure 5 is a view similar to Figure 4 illustrating how the sheets are assembled.

Referring now more particularly to the drawings, there are shown portions of two overlapping and interfitting sheets of expanded metal designated generally by reference numerals 2 and 25 2a, respectively. The expanded metal is of conventional form as made on a guillotine type expanded metal making machine and for most purposes will be what is known as heavy mesh weighing in the neighborhood of three to four pounds per square foot and having a thickness of the order of one-third of an inch. In a preferred form of structure the width of the strands may be about one-half inch, the width of the diamonds may be about three inches on centers and 30 the length of the diamonds may be about eight inches on centers. The sheets may be of any desired size, as, for example, four feet wide by twelve feet long.

The expanded metal has the usual strands 3 40 connected together at bonds 4. As is well known, the entire sheet of expanded metal is an integral piece of metal made from a sheet or plate. The strands are severed from one another for limited distances along the plate and are then stretched 45 to form the conventional diamonds.

Connected with the sheet 2, as, for example, by welding 8, is a bar 9 carrying an aligned series 50 or row of fastening or stop members each designated generally by reference numeral 5. As shown in Figure 1, these stop members are aligned in the direction parallel to the length of the diamonds and each is formed as an integral part of the bar 9 which in turn is welded to the sheet 2 at bonds 4 thereof. Each stop member or hook 5 comprises a connecting portion 6 lying in the

general plane of the bar 9 and a neck portion 7 forming a continuation of the connecting portion 6 but turned at approximately right angles thereto toward the plane of the sheet of expanded metal 2. In the structure shown in the drawings 5 the bar 9 is connected with one strand of the expanded metal at each bond 4 at each of two adjacent parallel rows of bonds of the expanded metal of the sheet 2 and the stop members project from the bar at the bonds of one row generally in the plane of the bar and at a slight angle to the plane of the sheet as shown in Figures 4 and 5 and have their ends or neck portions 10 turned so as to intersect the plane of the sheet and extend generally in the direction of the other strand at said respective bonds. The bar is adjacent but a diamond or two removed from the edge of the sheet.

Figures 4 and 5 illustrate how the sheets 2 and 2a with the bar 9 having the stop members 5 applied to the sheets 2 are fastened together. Referring to Figure 5, the left-hand sheet 2 viewing that figure is first laid on the ground with its stop members 5 pointing downwardly as shown. Another like sheet 2a then has the diamonds at its edges which is opposite the edge nearest which the stop means is applied to it positioned in the diamonds of the sheet 2 into which the stop members 5 of the sheet 2 project. In order to do this with the first sheet lying on the ground the second sheet is held in more or less vertical position. The edge diamonds of the second sheet enter the diamonds of the first sheet into which the stop members project as shown in Figure 5, after which the second sheet is turned down generally clockwise viewing Figure 5 until it is substantially coplanar with the first sheet but lies in overlapping relationship therewith, nested one diamond. When the sheets are in that position corresponding parts interfit as is well known to those skilled in the expanded metal art. The interfitting sheets are shown in inverted plan view in Figures 1 and 2, in plan view in Figure 3 and in cross section in Figure 4.

When the sheets are in interfitting position as shown in Figures 1 to 4, inclusive, they cannot move relatively to one another unless one of them is turned substantially out of the plane of the sheets to be disengaged from the other in the reverse of the manner of engagement above described. The sheets form a composite structure which is to all intents and purposes integral so far as transmission of forces in the plane of the structure is concerned. The sheets cannot move substantially toward or away from each other but can only remain in the position shown. They can, however, to a certain extent adapt themselves to unevenness in the ground.

Figures 1 and 2 of the drawings are inverted plan views to aid in a clear showing of the structure with the bar 9 positioned behind the expanded metal as viewed so as not to obscure the joint. When the expanded metal is laid the bars 9 are disposed at the upper surface of the composite structure. The bars project somewhat above the upper surface of the expanded metal and serve as anti-skid treads. As clearly shown in Figure 3, each bar 9 is wider intermediate the stop members 5 than at the places where the stop members are positioned. The edge 10 of the bar remote from the nearer edge of the sheet of expanded metal is straight and the opposite edge 11 is non-straight, having inclined portions 13 extending between the relatively narrow parts of the bar where the stop members 5 are connected

to it and the relatively wide portions of the bar intermediate the stop members. The relatively wide portions of the bar have short substantially straight edge portions 12 connecting the inclined edge portions 13. The portions of the bar immediately adjacent and underlying the edge portions 12 overlie an aligned series of bonds of the expanded metal where they are welded to the expanded metal as shown. Also the bar is welded to the bonds of an adjacent aligned row at portions of its straight edge 10 opposite the stop members 5. This staggered welding of the bar to the expanded metal makes for a very strong and rigid structure, the bar serving not only to provide and position the stop members 5 but also to reinforce and strengthen the expanded metal.

There are no separate fastening means which must be applied to the sheets of expanded metal to fasten them together, the sole fastening means being the bars 9 with the stop members 5 thereon cooperating with the edges of adjacent sheets. Consequently the danger that the workmen may fail to apply separate fastening means or may lose or mislay such means is obviated.

The stress exerted between adjacent sheets under load is transmitted largely by the metal of the sheets themselves rather than by the stop members 5 or bar 9, although the stop members participate in the stresses by maintaining the sheets in nested relationship.

While I have shown and described a present preferred embodiment of the invention it is to be distinctly understood that the invention is not limited thereto but may be otherwise variously embodied within the scope of the following claims.

I claim:

1. A sheet of expanded metal having a stop member connected therewith at a bond thereof removed from the edge of the sheet, the stop member extending generally toward the edge of the sheet and having its end turned toward the plane of the sheet.

2. A sheet of expanded metal having a stop member connected with one strand of the expanded metal at a bond where two strands are joined together, the stop member projecting from said bond generally in the plane of the sheet and having its end turned so as to intersect the plane of the sheet and extend generally in the direction of the other strand at said bond so as to engage over a portion of another sheet of expanded metal when the sheets are disposed in overlapping relation with corresponding parts interfitting to prevent separation of the sheets by relative movement in the plane of the sheets.

3. A composite structure comprising two sheets of expanded metal disposed in overlapping relation with corresponding parts interfitting and a stop member connected with one strand of the expanded metal of one of the sheets at a bond where two strands are joined together, the stop member projecting from said bond generally in the plane of the sheet and having its end turned so as to intersect the plane of the sheet and extend generally in the direction of the other strand at said bond and engaging over a portion of the other sheet to prevent separation of the sheets by relative movement in the plane of the sheets.

4. A sheet of expanded metal having an elongated member connected therewith at an aligned series of bonds thereof removed from the edge of the sheet and extending generally parallel to the major axes of the diamonds of the expanded metal, said member carrying a plurality of stop means each extending generally toward the edge

of the sheet and having its end turned toward the plane of the sheet.

5. A sheet of expanded metal having a metal bar welded thereto at an aligned series of bonds thereof removed from the edge of the sheet and extending generally parallel to the major axes of the diamonds of the expanded metal, the bar carrying a plurality of hooks each extending generally toward the edge of the sheet and having its extremity directed generally toward the plane of the sheet, each hook extremity being spaced from a bond of said series sufficiently to receive an edge strand of another sheet of expanded metal whereby to fasten the sheets together when they are disposed with their edges overlapping 15

and with corresponding parts of the expanded metal meshwork of the sheets interfitting.

6. A sheet of expanded metal having a stop member connected therewith and positioned at a point removed from the edge of the sheet, the stop member extending generally toward the edge of the sheet and having its end turned generally toward the plane of the sheet and positioned generally opposite a bond of the expanded metal but spaced from said bond in a direction generally toward the edge of the sheet sufficiently to provide for positioning of an edge portion of the meshwork of another sheet of expanded metal between the end of the stop member and said bond.

THEODORE S. OKONSKI.
